UNITED STATES PATENT OFFICE.

JAMES J. WARD, OF GREENE, OHIO, ASSIGNOR OF THIRTY-FIVE ONE-HUNDREDTHS TO
IVO C. DE BEUCKELAERE AND TWENTY ONE-HUNDREDTHS TO WALTER G.
MATTHEWS, BOTH OF DAYTON, OHIO.

SOUND-AMPLIFIER.

1,301,526.

Specification of Letters Patent. Patented Apr. 22, 1919.

Application filed September 19, 1917. Serial No. 192,184.

To all whom it may concern:

Be it known that I, JAMES J. WARD, a citizen of the United States, residing in the county of Greene, near the town of 5 Fairfield, State of Ohio, have invented new and useful Improvements in Sound-Amplifiers, of which the following is a specification.

This invention relates to new and useful 10 improvements in sound amplifiers.

The principal object of the invention is to provide a sound amplifier which is especially adapted for aviation service. It is particularly designed to meet the needs of 15 aviation instruction work, since the instrument will not accept the sound of the motor and other moving parts, to the end that the instructor may talk in a low tone to one or more students accompanying him, without 20 the necessity of using his hands or other means for signaling directions to them. The receivers, which are applied to the ears of the student, will so magnify the voice of the instructor, that everything he says will be 25 plainly audible amidst the almost deafening noise of the motor and other rotating parts.

My device is also particularly useful in war observation work, since it enables the 30 operator of the machine to converse with the observer under the most noisy and trying circumstances.

The instrument is not limited, however, in its application to aviation instruction and 35 observation service, but it may be useful in boats, buildings and other places where it is desired to transmit vocal and other sounds free from the disturbance created by extraneous noises.

40 The preferred form of embodiment of my invention is illustrated in the accompanying drawings, of which Figure 1 is a side elevational view of my sound amplifier, showing the receiver diaphragms in dotted lines. Fig. 2 is a top plan view of one of the receivers. And Fig. 3 is a longitudinal sectional view through one of them.

Throughout the specification and drawings, similar reference characters denote corresponding parts.

In a detailed description of the preferred form of embodiment of my invention, the numeral 1 designates a preferably bell-shaped mouth piece to the rear end of which

a line of rubber or other flexible tubing 2 is 55 suitably connected. The other end of this tubing is connected to a tubular Y 3, to each fork of which a piece of flexible tubing 4 is secured.

To the free end of each of the tubes 4, 60 there is connected a receiver 5 constructed as follows. Each receiver preferably comprises a hollow metallic member circular in cross section, and which is closed at the bottom and open at the top. (See Figs. 2 65 and 3). Its shape is similar to that of the ordinary vaseline box with the top removed. However, it may be of any other form or shape that will enable it to be readily fitted to the human ear, without departing from 70 the spirit of my invention.

At one point within the circular rim or receiver 5 there is provided a preferably circular hole 6, from which a preferably corrugated tubular boss 7 extends outwardly 75 to receive and hold firmly thereto, the free end of one of the tubes 4. (See Figs. 1 and 3.)

For the purpose of amplifying the sounds received from the tubes 4, each of the 80 receivers 5 contains a circular diaphragm 8. One end of this diaphragm is preferably soldered to the bottom of its respective receiver 5, at a point directly opposite the hole 6 therein, in such a manner that the opposite end of said diaphragm may approximately extend to the lateral plane of the horizontal axis of said hole. 85

Each diaphragm 8 has a slight clearance within its respective receiver 5 so that its 90 free end may vibrate in response to the sound waves entering the hole 6. In order that it may be more sensitive to said waves and vibrate more freely to magnify them for presentation to the ear of the auditor, the 95 diaphragm 8 has formed in its circular edge opposite the hole 6, a preferably semicircular notch or recess 9. This enables the sound conducting medium, which in this instance is air, to project its vibratory waves freely 100 against the plane surface of the diaphragm, that in turn amplifies them for contact with the ear drum.

The operation of the device in the aviation service will now be described. After 105 occupying his seat in the machine, the instructor firmly and comfortably secures the mouth piece 1 to his face so that he may

talk directly therein while keeping his eyes to the front. The student at the same time holds or otherwise secures the receivers 5 to his ears, and as the instructor talks to him in a low, direct tone, the sounds emitted by him will be so amplified by the instrument, that his directions will be distinctly audible to the student notwithstanding the noise of the whirling motor and other parts, 10 which he will not hear. In a like manner other sounds may be freely and distinctly transmitted, free from the disturbance created by extraneous noises.

I do not wish to be limited to the details 15 of construction and arrangement herein shown and described, and any changes or modifications may be made therein within the scope of the subjoined claims.

Having described my invention, I claim:

- 20 1. A sound amplifier comprising a hollow member closed at one end, and having a hole in the side portion thereof to admit sound waves, and a diaphragm within said member, one end of which is secured to the latter in such a manner as to project its other end into the direct path of the sound waves entering the member through said hole, for a vibratory movement by said waves.
- 30 2. A sound amplifier comprising a hollow member closed at one end, and having a hole in its side portion to admit sound waves, and a diaphragm having a notched portion, laterally disposed within said member, the end 35 of said diaphragm opposite its notched portion being secured within said member in such a manner as to project said notched portion into the direct path of the sound waves entering the member through said

hole, for a vibratory movement by said 40 waves.

3. A sound amplifier comprising a hollow cylinder having a hole in its side portion to admit sound waves, a bottom for said cylinder, a flat diaphragm, of slightly less 45 diameter than said bottom, laterally disposed within said cylinder, a recess formed in the peripheral edge of said diaphragm, and means for securing that part of said diaphragm opposite its recessed portion, to 50 the bottom of said cylinder, in such a manner as to project its notch portion into the plane of the lateral axis of said hole, for vibration by the sound waves entering the cylinder therethrough.

4. In a sound amplifier, the combination with a mouth piece, of a hollow cylinder closed at one end and having a hole in its side portion, a flexible tube connecting said mouth piece and hollow cylinder in such a 60 manner as to permit the sound waves from the former to enter the latter through said hole, and a diaphragm having a notched portion, laterally disposed within said hollow member, the end of said diaphragm opposite its notched portion being secured within said member in such a manner as to project said notched portion into the direct 65 path of the sound waves entering the member from the mouth piece through said tube 70 and hole, for a vibratory movement by said waves.

In testimony whereof I have hereunto set my hand this 17th day of September, 1917.

JAMES J. WARD.
